ANTENNA FOR A SIGNAL-RECEIVING DEVICE

Richard W. Cushing, Forest Park, and Roman Dereng, Berwyn, Ill., assignors to Warwick Manufacturing Corporation, a corporation of Delaware

Filed Mar. 29, 1957, Ser. No. 649,506

4 Claims. (Cl. 343—805)

This invention relates to an antenna and more particularly to an antenna for a signal-receiving device such as a portable television set or the like.

An object of this invention is to provide a new and improved antenna for a signal-receiving device.

Another object of the invention is to provide a new and improved antenna which may readily be adjusted to different operative positions or between an operative and an out-of-use position which is of simple and inexpensive construction and easily adjustable in use.

Another object of the invention is to provide an antenna for a portable television set in which the antenna has a pair of arms, each of a two-part construction which may be readily adjusted to vary their lengths and which are rotatably adjustable on a movable mounting member to permit alignment of the arms in a plane extending substantially parallel to the rear of the set so that rotation of the mounting member may carry the arms to a position behind and adjacent the back of the set to permit packaging or carrying of the set without interference from the antenna.

A further object of the invention is to provide an antenna comprising a pair of antenna arms of wire-like material, each arm being of a two-part construction, the parts of an arm each having a spiral portion formed from a length thereof in which the other part slides to provide for adjusting the length of the arm.

A still further object of the invention is to provide an antenna for a portable television set comprising, in combination, a disc-like mounting member formed of insulating material, means mounting said member on the back of the set for rotational movement in a plane substantially parallel to the back of the set, a pair of terminal members fastened to the mounting member to which lead-in wires for the set may be attached, each of said terminal members having a cylindrically shaped socket member associated therewith, and an antenna arm formed of wire-like material extending from each socket member and having a cylindrical connector at an end mounting the arm for rotation about an axis extending parallel to the plane in which the mounting member is moved, each arm having a bend formed therein at a location to lie above the top of the set and being of an extensible, two-part construction, whereby the arms may be positioned behind and adjacent the back of the television set or may be placed in operative position by rotation of the mounting member and rotation of the arms relative to the socket members.

The objects of the invention generally set forth together with other ancillary advantages are attained by the construction and arrangement shown by way of illustration in the accompanying drawing, in which:

Fig. 1 is a rear elevation of a support such as a portable television set, with the antenna shown in position behind and in back of the set;

Fig. 2 is a rear view in elevation similar to Fig. 1 on an enlarged scale, with the antenna shown in an opera-

2

tive position, and with the support for the antenna broken away;

Fig. 3 is a vertical section on an enlarged scale taken generally along the line 3—3 in Fig. 2;

Fig. 4 is a vertical section on an enlarged scale taken generally along the line 4—4 in Fig. 2; and

Fig. 5 is a plan view of an antenna arm, with parts thereof broken away.

While this invention is susceptible of embodiment in many different forms, there is shown in the drawings and will herein be described in detail an illustrative embodiment of the invention with the understanding that the present disclosure is to be considered as an exemplification of the principles of the invention and is not intended to limit the invention to the embodiment illustrated. The scope of the invention will be pointed out in the appended claims.

The antenna is shown mounted on the back of a support 1 which may be a signal-receiving device such as a portable television set. The antenna comprises generally a mounting member 2 which carries terminal members indicated generally at 3 and 4 and extensible antenna arms indicated generally at 5 and 6.

The disc-like mounting member 2 is formed of insulating material such as wood fiber hardboard. The mounting member is mounted for rotational movement in a plane substantially parallel to the back of the set 1 by a screw 7 which passes through an opening 8 centrally located in the mounting member.

Each of the terminal members 3 and 4 is constructed for self-fastening to the mounting member 2. For this purpose the mounting member 2 has two openings associated with each terminal member and, as shown in Fig. 3, has openings 9 and 10 associated with the terminal member 3. The terminal members are made of relatively thin metal plate and are constructed to have some flexibility as an aid in attaching the terminal member to the mounting member. Each of the terminal members is similar in construction, and terminal member 3, as shown in Fig. 3, will be described in detail as illustrative of both members.

The terminal member has a pair of flanges 15 and 16 at its ends and an intermediate section formed with a flexible, U-shaped bend 17 and a cylindrically shaped socket member 18 formed by turned-up flaps 19 and 20 which cooperate with a base section 21 of the terminal member. The intermediate section of the terminal member also has a member 22 rotatably threaded therein to which one end of a lead-in wire 23 may be secured. A similar lead-in wire 24 may be attached to the other terminal member 4, and the lead-in wires may be connected to members 25 and 26 at the back of the set or lead directly into the set.

The terminal member 3 is mounted on the mounting member 2 by first inserting the flange 15 through the opening 10 in the mounting member and then placing the intermediate section of the terminal member in the opening 10. As a final step, the flange 16 of the terminal member is extended through the opening 9 of the mounting member which is permitted by the flexibility of the terminal member. The terminal member 3 is then held on the mounting member 2 by the flanges 15 and 16 engaging a back side 27 of the mounting member 2. Although not a necessary part of the structure, a thin, disc-like sheet

28 of insulating material may be attached to the mounting member 2 by means of a rivet 29, and an annular spacer 30 is placed around the screw 7 to space the mounting member 2 from the support 1 to permit rotation of the mounting member 2 at a spaced distance from the support. The mounting member 2 is maintained in adjusted position by friction between the parts.

The antenna arms 5 and 6 are each of a two-part construction and have inner arms 35 and outer arms 36. The inner arms are each formed with a cylindrical connector 37 at one of their ends which is rotatably mounted in the associated socket member 18. The antenna arms are thus mounted for rotation about axes which are spaced from each other and lie in a common plane extending substantially parallel to the plane of movement of the mounting member 2 about the screw 7. The inner antenna arms 35 are each also formed with a bend, as indicated at 38, to locate the major part of the antenna arms at a level above the top of the set 1 when the antenna is in use, as shown in Fig. 2. The relative position of inner and outer antenna arms 35 and 36 may be adjusted relative to each other to vary the over-all length of the antenna arm. This is accomplished by having the inner antenna arm 38 formed with a spiral portion 40 at its outer end in which the outer antenna arm 36 is slidable. The outer antenna arm 36 has its inner end formed with a spiral portion 41 in which the inner antenna arm 35 may slide.

As shown in Fig. 1, when the signal-receiving device 1 such as a portable television set is packaged or is being transported, the mounting member 2 may be in position, and the antenna arms contracted so as to locate the antenna behind and adjacent the back of the set. When it is desired to use the antenna, the mounting member 2 may be rotated to the position of Fig. 2. The antenna arms 5 and 6 may be extended by sliding the inner and outer arms 35 and 36 through their associated spiral portions, and the antenna arms may be rotated to a desired position for receiving a particular signal by rotation of the cylindrical connectors 37 in the socket member 18. Return of the antenna to the position shown in Fig. 1 requires the rotation of the antenna arms 5 and 6 into a common plane, which is the plane of their axes of rotation and more particularly of the cylindrical connectors 37, contraction of the antenna arms 5 and 6, and rotation of the mounting member 2.

The antenna arms 5 and 6 may be formed from a wire material such as piano wire.

We claim:

1. An antenna for a portable television set comprising, in combination, a disc-like mounting member formed of insulating material, means mounting said member on the back of the set for rotational movement in a plane substantially parallel to the back of the set, a pair of terminal members fastened to the mounting member to which lead-in wires for the set may be attached, each of said terminal members having a cylindrically shaped socket member formed thereon, and an antenna arm formed of wire-like material extending from each socket member and having a cylindrical connector at an end mounting the arm in a socket member for rotation about an axis extending at a small angle relative to the plane in which the mounting member is moved, each arm having a bend formed therein at a location to lie above the top of the set when the arms extend upwardly, each arm being of a two-part construction, the parts of an arm each having a spiral portion at one end formed from a length thereof in which the other part slides to provide for adjustment of the over-all length of the arm for optimum operation of the set, whereby the arms may be positioned behind and adjacent the back of the television set or may be placed in operative position by rotation of the mounting member relative to the set and rotation of the arms relative to the socket members.

2. An antenna for a portable television set comprising, in combination, a mounting member, means for mounting said member on the back of the set for rota-

tional movement in a plane substantially parallel to the back of the set, a pair of terminal members fastened to the mounting member to which lead-in wires for the set may be attached, a cylindrically shaped socket member

5 connected to each of the terminal members, and an extensible antenna arm extending from each socket member and rotatably mounted therein, each arm having a bend formed therein at a location to lie above the top of the set when the arms extend upwardly, whereby the arms

10 may be positioned behind and adjacent the back of the television set or may be placed in operative position by rotation of the mounting member relative to the set and rotation of the arms relative to the socket members.

3. An antenna comprising, a mounting member having

15 means for rotatable attachment to a support surface for rotational movement in a plane substantially parallel to support surface, a pair of antenna arms, means pivotally mounting each of the arms at one of its ends to the mounting member for rotation about an axis, said axes

20 being spaced and offset from each other and lying in a common plane extending substantially parallel to the plane of movement of the mounting member, each of said arms having a part of its length extending coaxially with its axis of rotation, whereby the arms may be rotatably

25 positioned in said common plane to permit movement

of the mounting member and the arms therewith relative

to the support surface without interfering therewith.

4. An antenna comprising, a disc-like mounting mem-

30 ber having means for rotatable attachment to a support surface for rotational movement in a plane substantially parallel to said support surface, a pair of antenna arms, each arm being of a two-part construction with the parts

35 of an arm being slidably connected to each other, means mounting each of the arms at one of its ends to the mounting member for rotation about an axis, said axes

being spaced and offset from each other and lying in a common plane substantially parallel to the plane of movement of the mounting member, each of said arms

40 having a part of its length extending coaxially with said axis of rotation and the remainder thereof extending at an angle to the axis of rotation, whereby the arms may be positioned in said common plane to permit movement

45 of the mounting member and arms without engaging the support surface between a first position in which the arms

lie behind and in back of the support and a second posi-

tion in which the arms extend above the support surface

in positions to be extended and rotated to a desired oper-

ating position.
